UNITED STATES PATENT OFFICE.

ALBERT S. NEWBY, OF KANSAS CITY, MISSOURI.

DESIGN FOR A GRATE.

SPECIFICATION forming part of Design No. 26,493, dated January 5, 1897.

Application filed October 6, 1896. Serial No. 608,065. Term of patent 14 years.

To all whom it may concern:

Be it known that I, ALBERT S. NEWBY, a citizen of the United States, residing at Kansas City, in the county of Jackson and State of Missouri, have invented a certain new and original Design in a Combined Front and Bottom Grate; and I do hereby declare the following to be a full, clear, and close description hereof.

The leading features of my design consist in a front and bottom stove-grate in the same frame and arranging upon the frame certain projections, ribs, and grooves, with one or more holes through said frame, all of which will fully appear in the following specification and accompanying drawings, which form a part hereof, and in which—

Figure 1 represents a perspective view of my design. Fig. 2 is a cross-section through line X X of Fig. 1.

In the drawings the portion of the frame surrounding the bottom grate is designated by A. It has upon its upper surface wedge-shaped projections a. Along one end runs a rib b, and through the frame near the rib b are a number of oblong holes c. The grate

proper is constructed with two parallel bars B and cross-bars d, with journals C.

The front grate, which is set in the frame integral with the bottom grate, has a bar e 30 near the bottom and a wide plate D along the top, forming the upper portion of the frame. The bar e and the plate D are united by the cross-bars f. The side of the frame is thickened at g, and a longitudinal groove h 35 extends the entire length of the plate D near its upper edge. It will be seen that this unity of the two grates in one frame and the groove, rib, holes, and projections on said frame form a unique design.

What I claim, and desire to secure by Letters Patent, is—

The design for a front and bottom grate for stoves, as described and shown in the accompanying drawings.

In testimony whereof I affix my signature in the presence of two witnesses.

ALBERT S. NEWBY.

Witnesses:

B. F. PURSEL,

B. HOWARD SMITH.
